(57) **CLAIM**

We claim the ornamental design for an low intensity light imaging apparatus, as shown and described.

DESCRIPTION

FIG. 1 is a top perspective view of a low intensity light imaging apparatus showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a side elevation view of one side thereof; and,

FIG. 7 is a side elevation view of the other side thereof.
